UNITED STATES PATENT OFFICE.

LOUIS HERMANN, OF CHICAGO, ILLINOIS.

SHARPENING-TOOL.

1,305,602.

Specification of Letters Patent.

Patented June 3, 1919.

Application filed October 28, 1916, Serial No. 128,153. Renewed April 28, 1919. Serial No. 293,375.

To all whom it may concern:

Be it known that I, LOUIS HERMANN, a citizen of the United States of America, and resident of Chicago, Cook county, Illinois, 5 have invented a certain new and useful Improvement in Sharpening-Tools, of which the following is a specification.

My invention relates to improvements in tools, and more particularly to sharpening tools, or devices for the blades or knives of hair cutting shears, safety razors and the like, and the object of my invention is to provide an improved device of this character which will be simple, durable and reliable in construction, effective and efficient in operation and inexpensive to manufacture.

Other objects of my invention will appear hereinafter.

20 My invention consists in the features of novelty exemplified by the construction, combination and arrangement of parts hereinafter described, shown in the accompanying drawings and more particularly set 25 forth in the appended claims.

Referring to the drawings:

Figure 1 is a plan view of my improved device, showing a cutter or knife in position to be clamped;

30 Fig. 2 is a similar plan view showing the holder device in position for sharpening the lower blade of the hair cutting tool;

Fig. 3 is a transverse section on line 3—3 of Fig. 1;

35 Fig. 4 is a detail plan view of the holder shown in Fig. 2;

Fig. 5 is a detail end view of the holder shown in Fig. 4;

Fig. 6 is a detail transverse section on 40 line 6—6 of Fig. 2.

The cutting knives or shears A and B of the usual or standard hair cutters each have a series of prongs or projections C which coöperate with the prongs C of the 45 other cutter and in sharpening these cutters their coöperating faces D or surfaces are ground perfectly flat. The most satisfactory method of sharpening these cutters is to disassemble the structure and individually grind the faces of the knives on the smooth flat surface E of a hone or stone F of suitable material such as carborundum. Heretofore, however, it has been difficult when using these hones or stones to grind 55 the cutters uniformly and to properly maintain the knives or cutters in relation to the

stone during the sharpening operation. I employ a stone F which is preferably rectangular in shape so as to present smooth, flat grinding surfaces. In the surface I 60 provide a longitudinal groove G of any suitable, preferably rectangular, cross-section for the purpose of holding a removable guide member or bar H. This guide member is preferably of the same shape in cross 65 section as the groove or slot but when in place in said groove it rises above the grinding surface of the stone so as to provide a longitudinal shoulder or ledge J. This serves as a guide for the cutter. The operator places the cutter flat upon the stone surface, as shown in Figs. 1 and 3, with its rear edge J¹ against the guide shoulder and then reciprocates the cutter along the surface, applying sufficient pressure to the cutter by placing his finger upon the upper side 70 of the blade, and at the same time maintaining the cutter against the guide. This construction is provided for sharpening the upper blade of the standard cutting tool 75 because this is usually flat and thin. My improved device is adapted for sharpening the lower blade but on account of the difference in construction of the lower blade or knife, I provide a holder therefor. This 80 holder is preferably made up of sheet metal punched and formed to the proper shape in order to render the device as inexpensive 85 as possible. The structure shown in the drawings consists of a body plate L of metal 90 which is slightly curved to conform generally to the upper surface of the lower cutter, the cutter being positioned between the plate L and the stone. The opposite edges L¹ and L² are slightly curved in opposite 95 directions to form lips so as to insure the pressure of the hand being applied close to the edge of the cutter knife. This device is constructed in this manner so as to make it adaptable to different sizes of cutter knives, 100 the standard cutter being made for the market in two sizes, hence one side of the holder device is used for one size of cutter blade and the reverse side for the other size cutter blade. This is determined, however, by 105 the small lugs or projections L³ and L⁴ outstanding from opposite sides of the holder device. These lugs are preferably formed up from the edges of the plate L and are positioned substantially at right angles to 110 the plate. On the one side the lugs L³ are spaced a less distance apart than the lugs L⁴

- on the opposite side and are adapted to receive the smaller of the two sizes of cutter blades between them. The larger cutter blade is intended to fit between the lugs L⁴.
5 I preferably make the holder of a comparatively soft metal, such as brass, so that the lugs L³ and L⁴ may be bent slightly either way to take care of any slight deviations in the dimensions of the cutter blades. The
10 operator places the lower blade with its surface D upon the surface of the stone and then places the holder or operating device upon the blade using the side thereof corresponding to the size of the cutter blade.
15 The lugs L³ or L⁴, as the case may be, embrace the cutter blade and maintain it in position with respect to the holder. The operator then reciprocates the blade and holder along the grinding surface, exerting
20 the proper pressure for the purpose. The lugs L³ and L⁴ project considerably beyond the cutter blades and act as guide lugs by coöoperating with a longitudinal guide slot M in the stone, this being deep enough for
25 the purpose and of the proper cross-sectional shape. The lugs L³ or L⁴, as the case may be, which project upwardly serve as finger pieces or grips by which the operator may secure a firm yet convenient hold upon
30 the device. The cutter blades of standard cutters usually have a central hole or opening N which constitutes a means for holding the blades in position on the cutters, and this is utilized in my device for holding the
35 blade against any rotary movement. The plate L has central lugs L⁵ punched up and properly positioned so that they engage in the holes in the cutter blades. Thus the cutter blade is held at three points; that is by the two lugs L³ and L⁴, as the case may be, and by the central lug L⁵. It is obvious that the shape and size of the stone and the number and arrangement of the guide slots may be varied without departing from
40 the scope and spirit of my invention. The bottom surface O of the stone may be smooth and flat if desired for the purpose of honing the ordinary razor.
45 I claim:
50 1. The combination of a stone having a smooth grinding surface and a slot in said surface, and a removable guide bar in said slot projecting above the surface of the stone and forming a shoulder along which the device to be sharpened may be reciprocated. 55
2. The combination of a grinding stone having a flat grinding surface, a removable guide member mounted thereon and presenting a guide shoulder for the blade to be sharpened and along which the blade may be reciprocated in contact with the surface. 60
3. The combination of a stone having a smooth grinding surface and a slot in said surface, a removable guide bar in said slot 65 projecting above the surface of the stone and forming a shoulder against which the device to be sharpened may be simplified, a holding device adapted to be placed upon the device to be sharpened and to confine 70 the blade between the holder and stone, and means for guiding the blade and holder in a definite path along the stone.
4. The combination of a honing stone having a smooth flat surface and having two 75 parallel slots, a removable guide bar in one of said slots projecting above the surface of the stone and a separate blade holder for confining the blade between the holder and the surface of the stone and having 80 means to engage the side edges of the blade and project into the other slot to guide the holder and blade in a definite line of movement.
5. The combination of a honing stone having a smooth flat grinding surface and two 85 parallel slots or grooves in said surface, a removable guide bar in one of said slots and a blade holding device comprising a plate adapted to be positioned against the upper 90 side of the blade and having downwardly projecting lugs coöoperating with the said other slot or groove for guiding the plate in a definite line of movement. 95
Signed by me at Chicago, Illinois, this 26th day of October, 1916.
LOUIS HERMANN.
